CIRCUIT CHANGING SYSTEM

Edmond Michel, New Orleans, La., assignor to
Larmloc Corporation, New Orleans, La.Original application May 7, 1936, Serial No.
78,504. Divided and this application June 17,
1937, Serial No. 148,807

8 Claims. (Cl. 175—375)

The present invention relates to an improved circuit changing switch system and is a division under Official requirement of my copending application Serial No. 78,504, filed May 7, 1936.

An essential object of the invention consists in providing a circuit changing system including a switch having a relatively fixed contact with which is associated a movable contact for the purpose of normally establishing an electrical circuit with an operable member. The movable contact is in turn operatively associated with a key or plug contact whereby upon the engagement of the key contact with the movable contact to cause disconnection of the fixed contact from the movable contact and simultaneously to establish a circuit between the key contact and the movable contact. Additionally, means are provided for automatically returning the movable contact to engagement with the fixed contact upon withdrawal of the key contact from engagement with the movable contact.

A further object comprehends the provision of a circuit changing switch mechanism which may be readily associated with various types of electrical devices or systems and which is particularly applicable for use with electrical combination switches to change the combination of the electrical circuits connected to the operable members such as disclosed in my Patent No. 2,082,806, dated June 8, 1937.

Other objects and advantages of the invention will become apparent from the following description when taken in conjunction with the accompanying claims and drawing.

Referring to the drawing, in which is shown several preferred embodiments:—

Figure 1 is a diagrammatic view with parts in section showing my improved circuit changing switch mechanism associated with a two push button contact combination switch for actuating an electro-magnet and an alarm device;

Figure 2 is an end view of the switch casing with parts in section;

Figure 3 is a plan view of Figure 2 with portions of the cover cut away for clearness of illustration;

Figure 4 is a sectional view taken substantially along the line 4—4 of Figure 3, and

Figure 5 is a diagrammatic view of the circuit changing switch mechanism associated with a single push button contact combination switch.

Figure 6 is an enlarged sectional view of the push button switch mechanism.

Referring to the drawing, in which like numerals indicate like parts in the several views,

10 designates a casing which is shown as of elongated form but which obviously may be of any desired shape. The casing 10 is made of any suitable insulated material such as Bakelite, hard rubber or any other suitable composition, and 5 preferably comprises a recessed section 11 and a removable top or closure 12 for permitting ready access to the interior of the section 11. The inside of the section 11 is formed with the upwardly extending spaced partitions 13 and 14 (Figure 10 4) which align with complementary formed partition members 15 and 16 extending downwardly from the inner wall of the cover 12. The free ends of the aligned partitions are spaced from each other to form a series of longitudinally disposed openings 17 and 18. Each of the registering openings 17 and 18 constitutes a support for an electric conductive cylindrical member or rod 19 which is reciprocably mounted in the casing 10. Each of the rods 19 preferably comprises 20 an enlarged portion or sleeve 20 arranged normally to register with an aligned opening 21 in the front face plate 22 (Figure 3) and a reduced portion or stem 23 which projects through the opening 18 and is connected to the wire 24 which extends through the opening 25 in the rear face of the casing so as to be electrically connected to any suitable operable member. A coil spring 26 encircles the stem 23 and is confined between the annular flange or shoulder 27 on the sleeve 20 30 and the partitions 14 and 16 so as normally to urge each rod 19 to assume the position as shown in Figure 3 so that the outer ends of the movable contacts align with adjacent sockets 21. A fixed contact or conductive bar 28 preferably of 35 U shape (Figure 2) has its parallel arms 29 extending substantially the length of the interior of the casing so as to straddle the reciprocating rods 19 in order that these arms may be engaged by the shoulders 27. One side of the casing 10 40 may have a recess or groove 30 in the inner wall thereof for receiving the connecting arm of the U-shaped contact 28 so as to maintain the same in a fixed position within the casing 10. The 45 arms 29, it will be observed, are arranged to be engaged by opposite portions of each of the shoulders 27 so that when these shoulders are urged into engagement with the fixed contacts by the springs 26, means are provided for insuring a positive and uniform contact between 50 these parts.

The arms 29 are connected by the terminal screw 31 to a wire 32 which in turn is connected to any suitable source of electrical energy such 55

as a battery or the like which will subsequently be described.

A removable contact key or plug 33 preferably has an enlarged head or shoulder 34 arranged to fit into a complementary keyhole slot or socket 35 in the face plate 22 of the casing. The key contact 33 is electrically connected to any suitable operable member by the wire 36. The key 33 is detachably connected to the casing upon the insertion of the shoulder 34 into the socket 35 and the subsequent turning of the key so as to bring the shoulder 34 into engagement with the inner wall of the casing. Manifestly, the shape and size of the key 33 and socket 35 may be varied depending upon the shape of the casing 10 and the form of the fixed and movable contacts 19 and 28, respectively.

Any number of reciprocating contacts 19 may be employed corresponding to the number of circuits with which the device is associated. It will be seen that normally when the key 33 is withdrawn from the casing 10, the spring 26 causes the axial movement of the reciprocating rod 19 to move the flange or collar 27 into engagement with the arms of the fixed contact 28 to close a predetermined electrical circuit. Upon the selective insertion of the key 33 in any one of the openings 21 (Figure 4), the outer end of the key abuts against the adjacent end of the movable contact 19 and forces the same inwardly against the tension of the spring 26 to disconnect the engagement of the collar 27 with the fixed contact 28 and simultaneously establishes a separate circuit between the contact key 33 and the reciprocating or movable contact 19. Upon turning the key 33 either in a clockwise or counter-clockwise direction, the shoulders or lugs 34 are moved out of registration with the slots 35 and abut against the inner wall of the face plate so as to detachably secure the key to the casing. When it is desired to break the circuit between the key 33 and the movable rod 19, it is merely necessary to withdraw the key 33 from the casing. Upon the withdrawal of the key 33, the spring 26 causes the rod 19 to be moved axially and thus brings the collar 27 into engagement with the fixed contact 28 to re-establish the circuit which had been previously disconnected by the insertion of the key within the casing.

It will be seen that by reason of the novel arrangement of parts a practical and foolproof switch mechanism is provided for normally closing a predetermined circuit and for automatically disconnecting this circuit and establishing another circuit upon the insertion of a contact member within the casing, the original circuit being immediately reestablished when the contact member is withdrawn. Thus, the dangerous and disastrous consequences which result from the failure to properly disconnect a circuit before connecting another circuit is avoided, since the mechanism insures the automatic disconnection of a predetermined circuit immediately upon the establishing of another circuit. Moreover, the spring 26 acts to urge the movable contacts outwardly and in the direction of the sockets 21 in order to maintain the same normally in contact and in engagement with the fixed contact. This outward pressure serves a double purpose. When the key contact is inserted into the selected socket to disconnect the movable contact from the fixed contact, a slight pressure must be exerted against the normal position of spring 26 by the key contact,

then the key contact is slightly turned in either direction, and the pressure induced by spring 26 is transmitted to the outer end of the movable contact, which pressure is transmitted outwardly to the key contact and holds transverse arms or lugs 34 securely tight against the inner wall of face plate 22, and prevents the accidental disconnection of the key contact from the selected movable contact.

The top or cover 12 is detachably secured to the casing by the screws 37 to permit convenient access into the interior of the casing 10 for the purpose of inspection or removal of the parts. While the casing has been described as preferably made of insulatable material, it will be manifest that by this is meant the parts of the casing which constitute the supports for the movable contacts are of suitable insulatable material in order to separate the fixed contact and the movable contacts and thus insure the selective establishment of the separate circuits with each of the movable contacts.

While my improved circuit changing switch mechanism is adapted for use in changing the combination of various types of electrical devices, I have, for the purpose of illustration, shown the same associated with a two button combination switch for selectively controlling the flow of current to means for actuating a door lock or to a signalling device for indicating that the switch mechanism is being tampered with such as disclosed in my aforesaid Patent No. 2,082,806.

The switch 38 is preferably in the form of a casing panel 60 (Figure 6) and has mounted therein a transverse web 61 of insulated material to which may be threaded or otherwise connected a series of spaced fixed contacts 62 corresponding in number to the reciprocating contacts 19. A cover plate 63 closes the outer side of the casing and has a plurality of openings 64 which register with the adjacent fixed contacts 62 and slidably carry the push buttons or other suitable actuating means 65. A metallic plate or disc 66 secured to the underside of the cover 63 by a threaded bolt 67 and nut 68 and may be spaced from the plate 63 by an insulating washer 69. The plate 66 is formed with a series of spaced radially disposed flexible arms 70 corresponding in number to the fixed contacts 62. The arms 70 are interposed between adjacent contacts 62 and push buttons 65. The plate 66 through its arms 70 constitute a movable contact common to the fixed contacts 62 for the purpose of establishing predetermined circuits with the adjacent fixed contacts. The plate 66 is preferably formed of flat flexible metal so that when each of the arms 70 is displaced by a push button 65, it will be brought in engagement with its adjacent fixed contact 62, and will upon the release of the push button be returned to its normal horizontal position so as not to be detrimentally affected, by constant usage. The arms 70 are normally spaced from the fixed contacts 62 while the bolt 67 serves as means for establishing an electrical connection between the movable contact 66 and an operable member in a manner as will be subsequently described.

As shown in Figure 1, the circuit changing switch mechanism is provided with eight reciprocating contacts 19 corresponding in number to the number of push button contacts carried by the combination switch 38. Assuming that in the two button combination switch the means

and 7 have been selected to be the contacts necessary to be actuated in order to cause the operation of the electro-magnetic means 39, which controls the movement of the wedge member 39' associated with the lock or bolt 40, and that the remaining buttons 2, 3, 4, 5, 6 and 8 are arranged to control the electrical connection to the alarm 41. In such an event, each of the wires 24 leading from the reciprocating or movable contacts 19 is connected separately to one of the fixed contacts 62 of the double switch 38, and the fixed contact 28 is connected by the wire 32 to the positive side of the battery 42.

The plug or key contact 33 which is inserted through the opening 21 of the casing 10 in the circuit of the reciprocating contacts 19 connected to the fixed contact 62 associated with the push-button 1, establishes a connection between operable member 39 and the said fixed contact 20 through the wires 24 and 36, while the plug contact 33 inserted in the circuit of the other reciprocating contact 19 connected with the fixed contact 62 associated with the push-button 7, is connected by its wires 24, 36 and 43, battery 25 44 and wire 45 with the other side of the operable member 39. Consequently, when the push-button contacts 1 and 7 are simultaneously displaced to bring the arms 70 of the movable contact 66 into engagement with their adjacent fixed contacts 62, there is established an energizing circuit between the operable member 39 and its source of energy. A switch or relay 46 may be interposed in the circuit for controlling the same at a remote point. The remaining fixed contacts associated 30 with the push buttons 2, 3, 4, 5, 6 and 8 are connected on one side through the reciprocating contacts 19, fixed contact 28 and wire 32 with the battery 42, which in turn is connected by the wire 71 to one side of the magnet 49, while the movable contact 66 is connected through the bolt 40 67 and the wire 48 with the other side of the magnet 49. Thus, it will be seen that if anyone of the push buttons 2, 3, 4, 5, 6 and 8 is displaced, it will immediately close a circuit to the magnet 49 which in turn will actuate the relay 50 to move 45 the same into engagement with the contacts 50 and 51, thus energizing the alarm 41 to notify the proper authorities that the switch is being tampered with.

It will be seen that when my circuit changing switch is associated with a combination switch such as 38 for selectively controlling the supply of current to two or more operable members such as the magnet 39 and the alarm 41, that the two selected contacts establish a circuit with one of the operable members such as 39 while the remaining contacts are in circuit with the other operable members. Further, the combinations may be easily changed by pulling out the plugs 50 33 from the sockets 1 and 7 and reinserting them in other selected sockets. Manifestly, the number of contacts employed may be varied depending upon the purpose for which the circuit changing switch is to be used. The switch structure shown 55 in Figure 6 is substantially similar to the switch mechanism embodied in my copending application Serial No. 68,124, filed March 10, 1936.

The circuit changing switch is equally adapted for use with a single button combination or a dual control combination. As shown in Figure 5, 60 a single push button switch combination is disclosed for effecting the selective control of the operable members. Assuming that the push button 1 and its associated fixed contact 62 have been selected to control the actuation of the lock 65

or bolt 40, the plug 33 connected to the magnet 39 through wire 36 is inserted within the opening 21 with which aligns the reciprocating member 19 connected to the fixed contact 62 associated with the push button 1, while the other reciprocating contacts 19 will be maintained by their spring 26 in engagement with the stationary contact 28 as the wire 36 associated with the push button 7 (Figure 1) connected to the battery 44 is now dispensed with, the said battery 44 is 10 now connected to bolt 67 by line 48 in order to establish a circuit connection through the plug contact 33 connected to the individual fixed contact associated with button 1, through the positive side of battery 44, line 45 to magnet 39, then 15 through line 36 and bolt 67 to the movable contact 66, (Figure 6) when the arm of the movable contact 66 is moved in engagement with the fixed contact associated with button 1, then to plug contact 33 through line 24 and to the negative 20 side of battery 44 through line 48. The remaining contacts 2 to 8 inclusive are connected to the alarm 41 in substantially the same manner as shown in Figure 1. Thus, the removable contact 33 connected to magnet 39 may selectively 25 engage any one of the reciprocating contacts 19 to move the same out of engagement with the stationary contact 28 so that upon the actuation of the push button associated with the individual fixed contact 62 connected to the reciprocating 30 contact engaged by the plug contact, it will establish a circuit connection between the arm of the movable contact 66 and the said fixed contact and close the circuit to effect the actuation of the operable member 39. 35

The lock 40 and the alarm 41 constitute separate operable members which may be selectively connected to the movable contacts as desired. The alarm 41 is normally connected to the movable contacts 19 through the fixed contact 29 and 40 the wire 32 while a lock 40 is selectively connected to the same movable contacts through either the key contacts 33 as shown in Figure 1 or the single key contact shown in Figure 5. Heretofore, the key or plug contacts have been arranged 45 to operate or energize operable members immediately upon the closing of the key circuit. It is significant to note that in the present invention the operable members are not energized by the selective connection of the key contacts with 50 the movable contacts but are only rendered operative by the closing of the proper circuit through the switch 38. The push button contacts 1 to 8, inclusive, of the switch 38, therefore constitute control members, each of which is permanently 55 and individually connected to one of the movable contacts 19 so as to selectively control the actuation of the operable members associated with the electrical system.

It will therefore be seen that when the circuit 60 changing switch mechanism is associated with an electrical combination switch, the selected combination for controlling the operable members may be readily changed by withdrawing the plug 33 from its socket 35 and inserting the same in 65 any one of the other sockets so as to effect a change of the combination necessary to actuate the operable members 39 and 40 respectively.

Manifestly, the circuit changing switch mechanism may be operatively associated with various types of electrical devices for closing a predetermined electrical circuit and automatically opening said circuit and establishing another circuit while disconnecting the previously connected circuit. The insulated casing 10 and its 75

associated parts are very compact and may be conveniently positioned at any desired point to effect the change of the circuits by the selective insertion of the plugs 33 into the sockets 35.

5 It is to be understood that the forms of the invention shown and described are merely illustrative of preferred embodiments and that such changes may be made as fall within the purview of one skilled in the art without departing from 10 the spirit of the invention and the scope of the appended claims.

I claim:—

1. In a system of the class described, the combination of a control switch having spaced fixed 15 contacts, a contact having a plurality of movable contacts associated with the fixed contacts and normally spaced therefrom, means to bring the movable contacts in engagement with their associated fixed contacts, a source of electrical energy, 20 an electrically operable member, means interconnecting the operable member to the movable contacts, a circuit closing mechanism including reciprocating contacts, each of the reciprocating contacts being permanently connected to one of 25 the fixed contacts, and detachable contact means connected to the source of energy and arranged selectively to engage any one of the reciprocating contacts so that upon the actuation of the movable contact associated with the fixed contact 30 connected to the reciprocating contact engaged by the detachable contact means, to establish a circuit connection between the movable contact and the detachable contact means to actuate the operable member.

35 2. In a system of the class described, the combination of a control switch having spaced fixed contacts, a contact having a plurality of movable contacts associated with the fixed contacts and normally spaced therefrom, means to bring the movable contacts in engagement with their associated fixed contacts, a source of electrical energy, an electrically operable member, means interconnecting the operable member to the source of energy, a circuit closing mechanism including reciprocating contacts, each of the reciprocating contacts being permanently connected to one of the fixed contacts, detachable contact means connected to the operable member and the source of energy, said detachable 40 means arranged selectively to engage any one of the reciprocating contacts so that upon the selective actuation of the movable contact associated with the fixed contacts connected to the reciprocating contacts engaged by the detachable contact means, to establish a circuit connection through the said detachable means to actuate the operable member, a stationary contact, means for normally maintaining each of the reciprocating contacts in engagement with the stationary contact, a second operable member, means connecting the second operable member to the movable contacts, a second source of electrical energy, means connecting the stationary contact to the second source of energy so that upon the actuation of any one of the movable contacts associated with the fixed contacts not connected with the reciprocating contacts engaged by the detachable contact means, to establish a circuit connection between the movable contact and the stationary contact to actuate the second operable member.

60 3. In a system of the class described, the combination of a control switch having spaced fixed contacts, a contact having a plurality of movable contacts associated with the fixed contacts

and normally spaced therefrom, means to bring the movable contacts in engagement with their associated fixed contacts, a source of electrical energy, an electrically operable member, means inter-connecting the operable-member to the 5 source of energy, a circuit closing mechanism including reciprocating contacts, each of the reciprocating contacts being permanently connected to one of the fixed contacts, a pair of detachable plug contacts, means connecting one 10 of the said plug contacts to one side of the operable member, means connecting the other plug contact to the source of energy, each of the plug contacts arranged selectively to engage any one of the reciprocating contacts so that upon the 15 selective actuation of the movable contacts associated with the fixed contacts connected to the reciprocating contacts engaged by the two plug contacts, to establish a circuit connection between the said plug contacts to actuate the operable 20 member.

4. In a system of the class described, the combination of a control switch having spaced fixed contacts, a contact having a plurality of movable contacts associated with the fixed contacts and normally spaced therefrom, means to bring the movable contacts in engagement with their associated fixed contacts, a source of electrical energy, an electrically operable member, means inter-connecting the operable member to the 25 source of energy, a circuit closing mechanism including reciprocating contacts, each of the reciprocating contacts being permanently connected to one of the fixed contacts, a pair of detachable plug contacts, means connecting one of 30 the said plug contacts to one side of the operable member, means connecting the other plug contact to the source of energy, each of the plug contacts arranged selectively to engage any one of the reciprocating contacts so that upon the 35 selective actuation of the movable contacts associated with the fixed contacts connected to the reciprocating contacts engaged by the two plug contacts, to establish a circuit connection between the said plug contacts to actuate the operable 40 member, a stationary contact, means for normally maintaining each of the reciprocating contacts connected to the stationary contact, a second operable member, means connecting the second operable member to the movable 45 contacts, a second source of electrical energy, means connecting the stationary contact to the second source of energy so that upon the actuation of any one of the movable contacts associated with the fixed contacts not connected with the reciprocating contacts engaged by the two plug contacts, to establish a circuit connection between the movable contacts and the stationary contact to actuate the second operable member.

5. In a system of the class described, the combination of a control switch having spaced fixed contacts, a contact having a plurality of movable contacts associated with the fixed contacts and normally spaced therefrom, means to bring the movable contacts in engagement with their associated fixed contacts, a source of electrical energy, an electrically operable member, means inter-connecting the operable member to one side of the source of energy, a circuit closing mechanism including reciprocating contacts, each of the reciprocating contacts being permanently connected to one of the fixed contacts, a pair of detachable plug contacts, means connecting one of 60 the said plug contacts to one side of the operable member, means connecting the other plug contact to the source of energy, each of the plug contacts arranged selectively to engage any one of the reciprocating contacts so that upon the selective actuation of the movable contacts associated with the fixed contacts connected to the reciprocating contacts engaged by the two plug contacts, to establish a circuit connection between the movable contacts and the stationary contact to actuate the second operable member.

65 6. In a system of the class described, the combination of a control switch having spaced fixed contacts, a contact having a plurality of movable contacts associated with the fixed contacts

70 75 7. In a system of the class described, the combination of a control switch having spaced fixed contacts, a contact having a plurality of movable contacts associated with the fixed contacts

tact to the source of energy, each of the plug contacts arranged selectively to engage any one of the reciprocating contacts so that upon the simultaneous actuation of the two push buttons associated with the fixed contacts connected to the reciprocating contacts engaged by the two plug contacts, to establish a circuit connection through the plug contacts and the movable contacts to effect the actuation of the operable member.

5 6. In a system of the class described, the combination of a control switch including spaced fixed contacts, a contact having movable contact arms registering with adjacent fixed contacts and normally spaced therefrom, means to bring the 10 arms of the movable contact in engagement with their adjacent fixed contacts, a source of electrical energy, an operable member, means interconnecting the operable member to one side of the source of energy, a circuit closing mechanism including reciprocating contacts, each of the reciprocating contacts being permanently connected to one of the fixed contacts, a stationary contact, means for normally maintaining each of the reciprocating contacts in engagement with the 15 stationary contact, a second operable member, a second source of electrical energy, means connecting the second operable member to the movable contact, means connecting the stationary contact to the second source of energy, a pair 20 of detachable plug contacts, one of the said plug contacts being connected to the operable member and the other plug contact being connected to the source of energy, each of the plug contacts arranged selectively to engage any one of the reciprocating contacts so that upon the simultaneous actuation of the arms associated with the 25 fixed contacts connected to the reciprocating contacts engaged by the two plug contacts, to establish a circuit connection through the plug contacts and the movable contact to effect the actuation of the second operable member.

30 7. In a system of the class described, the combination of a control switch having spaced fixed contacts, a contact having a plurality of contact arms, each of said arms registering with adjacent 35 fixed contacts and normally spaced therefrom,

means associated with said arms for moving the same in engagement with their adjacent fixed contacts, a source of electrical energy, an electrical operable member, means interconnecting the operable member to the source of energy, a 5 circuit closing mechanism including reciprocating contacts, each of the reciprocating contacts being permanently connected to one of the fixed contacts, and a detachable plug contact connected to the operable member and arranged 10 selectively to engage any one of the reciprocating contacts so that upon the actuation of the arm of the contact associated with a fixed contact connected to the reciprocating contact engaged by the plug contact, to establish a circuit connection 15 between the arm of the contact and the plug contact to actuate the operable member.

8. In a system of the class described, the combination of a control switch including spaced fixed contacts, a contact having a plurality of contact 20 arms, each of said arms registering with adjacent fixed contacts and normally spaced therefrom, means to bring the arms of the contact in engagement with their adjacent fixed contacts, a source of electrical energy, an operable member, 25 means interconnecting the operable member to a source of energy, a circuit closing mechanism including reciprocating contacts, each of the reciprocating contacts being permanently connected to one of the fixed contacts, a stationary 30 contact, means for normally maintaining each of the reciprocating contacts in engagement with the stationary contact, a second source of electrical energy, a second operable member, means connecting the second operable member to the 35 contact, means connecting the stationary contact to the second source of energy, a detachable plug contact connected to the first operable member and arranged selectively to engage any one of the reciprocating contacts so that upon actuation 40 of the contact arm associated with the fixed contact connected to the reciprocating contact engaged by the plug contact, to establish a circuit connection between the contact arm and the plug contact to effect the actuation of the operable 45 member, the actuation of any one of the other contact arms being operable to close the circuit between the stationary contact and the movable contact to effect the actuation of the second 50 operable member.

EDMOND MICHEL.
